STEAM SUPERHEATER

Henry Edward Geer, London, England, assignor
to The Superheater Company, New York,
N. Y.

Application August 31, 1932, Serial No. 631,210,
and in Great Britain September 18, 1931

3 Claims. (Cl. 122—476)

This invention relates to steam superheater of the type in which the individual elements in a group or groups or banks of superheater elements (usually and preferably elements of the return bend or U-loop type) have their steam inlet and outlet ends connected to separate headers and extend downwardly and depend from the headers. Such a superheater may be one associated with a stationary steam generator or boiler of the multi-drum type, for instance a tri-drum boiler. In a boiler of the type above-mentioned there may be as usual two headers, each of which may be tubular and circular in cross section, the saturated steam distributor or header conveniently being disposed above the superheated steam receiver or header.

The present invention has for its principal object to provide a method of and means for counteracting or neutralizing the severe strains and stresses set up on the headers by the weight of the depending elements, which strains and stresses, by tending to rotate the headers about their longitudinal axes, are liable to result in serious damage to the means employed for supporting and securing the headers in position, and also to steam pipes or other fittings which may be connected to the headers.

Heretofore so far as I am aware no method or means has been provided to counteract the tendency of the weight of the elements of a superheater of the kind indicated above to rotate the headers about their axes.

In its broadest aspect the invention consists in the provision in a steam superheater of means whereby the load on a header tending to rotate it in its mountings is counteracted or substantially balanced by the load on, and tending to rotate, another header of the superheater. In other words the invention consists in utilizing the load of the elements distributed on to one header and tending to rotate it on its axis to balance, or substantially balance, the load of the elements distributed on to the other header and similarly tending to rotate such other header about its axis.

The invention further consists in the combination with the headers of a steam superheater having depending superheater elements so disposed and connected to the said headers that their weight tends to rotate both headers about their axes in the same direction of a plate or strap-like member of sinuous or S-like form and means securing said plate or member to the headers with its oppositely facing concave surfaces lying close to oppositely facing portions of the periph-

eral surfaces of the respective headers, whereby the load of the elements directly distributed on and tending to rotate a header is transmitted to and tends to rotate the other header in a direction opposite to that in which the load of the elements directly distributed on it tends to rotate it.

In the accompanying drawings:—

Fig. 1 is a sectional elevation of a portion of a tri-drum water tube boiler having a steam superheater to the headers of which anchoring means according to the present invention are applied.

Fig. 2 is an enlarged sectional view of the headers shown in Fig. 1 and illustrating one embodiment of the header anchoring means according to the present invention.

Fig. 3 is a view of portions of the headers shown in Fig. 2 equipped with the anchoring means therein shown as seen from the left of that figure, and

Fig. 4 is a view similar to Fig. 2 but illustrating other embodiments of the invention which will be described hereinafter.

Referring first to Fig. 1, 1 is the steam and water drum of the boiler, 2 being the front bank of water tubes, 3 the circulators from the other steam and water drum and 4 the equalizing tubes; 5 and 6 indicate U-loop or serpentine superheater elements, the inlet portions 7, 7^a of which are connected to the saturated steam header 9 and the outlet portions 8, 8^a of which are similarly connected to the superheater steam header 10, the headers 9 and 10 being arranged one above the other and carried in any usual or appropriate cradles or mountings, and clamped in position by means such as the usual U-shaped straps. An examination of Fig. 1 will show that the superheater elements 5 and 6 are connected to the headers 9 and 10 and along a portion of their periphery to the left of the longitudinal vertical plane through the centre of the headers and above the central horizontal planes of the respective headers. This is a well known arrangement of headers and elements and whilst efficient in most respects is subject to a disadvantage in that the weight of the depending elements tends to rotate the headers about their longitudinal axes. As above indicated it is the object of the present invention to provide means to overcome this disadvantage and according to the present invention the headers are anchored to one another by means which will now be described.

In the embodiment of the invention shown in Figs. 2 and 3 the headers are secured together

or anchored to one another by an S shaped strap or plate 11 the concave surfaces of which lie close to oppositely facing portions of the peripheral surfaces of the respective headers as will be clearly seen in Fig. 2. The straps 11 are secured to the headers by screws 12 extending through holes in the strap and engaged in tapped holes in the header wall.

It will be appreciated that in the superheater construction and arrangement shown in Fig. 1 the weight of the elements tends to rotate both headers in an anti-clockwise direction about their longitudinal axes. In a superheater equipped with anchoring means according to the invention and as shown in Figs. 2 and 3 a strain or load put upon the lower header 10 tending to rotate it in an anti-clockwise direction will be transmitted through the strap 11 to the header 9 and tend to rotate such header in a clockwise direction against the weight of the elements which are tending to rotate said header in an anti-clockwise direction. Thus the load on the lower header will be counteracted or neutralized by the load on the upper header. Similarly of course the load tending to rotate the upper header is balanced or counteracted by the load on the lower header.

In the construction shown in Figs. 2 and 3 the strain on the strap 11 is transferred from one header to the strap and from the strap to the other header through the screws 12. In the alternative embodiment of the invention shown in Fig. 4 each header has welded to it two blocks 13, and two blocks 14 are welded to each concave face of the strap 11. The blocks on the headers and strap are so disposed in relation to one another that the adjacent faces of each two blocks 13, 14 abut against one another and the blocks serve to transmit the strains from the headers to the strap and vice versa. The blocks associated with the upper header 9 in Fig. 4 are shown with their engaging faces radially of the header whereas the surfaces of the blocks 13 secured to the header 10 are undercut and the engaging faces of the blocks 14 correspondingly formed. The strap 11 in the construction shown in Fig. 4 is secured to the headers by screws 12 extending into tapped holes in the blocks 13.

In the embodiment of the invention shown in Figs. 2 and 3 the concave surfaces of the strap snugly fit the peripheral surfaces of the headers. In the construction shown in Fig. 4 the concave surfaces of the strap 11 are spaced from the peripheries of the headers by the provision of the

blocks 13 and 14 but the strap is so formed that its intermediate or straight portion contacts with the peripheries of the headers at the points marked 15 in Fig. 4.

The invention is not restricted to the number of straps employed on any given pair of headers, but usually two straps relatively close together approximately mid-way of the length of the headers will be found sufficient. Also the invention is not restricted to the straps being secured to headers by the means shown in the drawings as other means might be employed, for instance the straps might be welded to the headers. Also it is to be understood that the invention is not restricted to steam superheaters comprising two headers only as it may be employed in superheaters having more than two headers but with the elements so disposed and connected to the headers that the weight of the elements tends to rotate the headers about their longitudinal axes. Further the anchoring means according to the present invention may be applied to headers arranged otherwise than in the same vertical plane.

What I claim is:

1. The combination of a plurality of headers supported at their ends so that each header is free of the weight of the other, at least between supports, fluid conducting means connected thereto intermediate the support therefor and so arranged that the weight of such means tends to rotate said headers, and a member connected between said headers and so arranged that the tendency of one header to rotate is transmitted to another and reacts against the tendency of such other header to rotate.

2. A steam superheater comprising two headers supported at their ends so that each header is free of the weight of the other at least between supports and superheater elements connected thereto intermediate the support therefor and so disposed that the weight of said elements tends to rotate said headers about their longitudinal axes, and a member connected between said headers and so arranged that the tendency of one header to rotate is transmitted to the other and reacts against the tendency of such other header to rotate.

3. A steam superheater as set forth in claim 2 and in which the superheater elements tend to rotate both headers about their axes in the same direction, and in which the member connected between the headers is a strap of S-like form.
